HAND SEAMER FOR CANS

Alfred L. Kronquest, Syracuse, N. Y., assignor to
 Continental Can Company, Inc., New York,
 N. Y., a corporation of New York

Application September 21, 1933, Serial No. 690,488

15 Claims. (Cl. 113—23)

The invention relates to new and useful improvements in a hand seamer for cans.

An object of the invention is to provide a simple form of construction whereby a can may be rotated by hand and an end automatically seamed thereto through the operation of the rotating means.

Another object of the invention is to provide a hand seamer wherein a differentially operated planetary gear may be utilized for driving the operating means for the seaming rolls of a hand seamer.

A still further object of the invention is to provide a hand seamer having an actuated gear traveling bodily about the axis of the control cam for the seaming rolls with a positive connecting means whereby said traveling gear operates said cams, so that they are rotated in synchronism.

A still further object of the invention is to provide a simple means for positively lifting the support for the can so as to chuck the can, which lifting means yieldingly holds said can support in raised position.

These and other objects will in part be obvious and will in part be hereinafter more fully disclosed.

In the drawings:—

Figure 1 is a view partly in side elevation and partly in section showing a hand seamer embodying the improvements;

Figure 1a is a view of a portion of the machine shown in Fig. 1, with the can support raised for chucking the can;

Fig. 2 is a plan view of the hand seamer;

Fig. 3 is a sectional view on the line 3—3 of Fig. 4;

Fig. 4 is a sectional view on the line 4—4 of Fig. 2;

Fig. 5 is a sectional view on the line 5—5 of Fig. 2, with the exposed parts of the frame and the seaming rolls omitted;

Fig. 6 is a sectional view on the line 6—6 of Fig. 2, with the exposed parts of the frame and the seaming rolls omitted;

Fig. 7 is a view partly in vertical section and partly in front elevation of a modified form of hand seamer;

Fig. 8 is a plan view of the same with the shaft in section and the crank removed, and

Fig. 9 is a sectional view on the line 8—9 of Fig. 7.

The hand seamer includes a supporting frame which is adapted to be attached to a table.

Mounted in the frame is a rotating shaft carry-

ing a chuck. This shaft is held from endwise movement by suitable means. Located directly beneath the chuck and mounted for rotation on the frame is a can support. Means is provided for lifting the can support to cause the can to engage the chuck. This lifting means includes a yielding element, and is also so constructed as to positively hold the support raised. Mounted on the frame at opposite sides thereof are seaming devices, each of which includes a seaming roll, 10 an arm carrying the seaming roll, and an actuating lever adapted to move the arm and carrying a roller cooperating with the control cam. The control cam is mounted for free rotation concentric to the axis of the shaft carrying the 15 chuck. Said control cam is rotated by a gear which is mounted on an eccentric member carried by the shaft. Said gear meshes with an internal gear fixed to the frame. Suitable hand means is provided for rotating the shaft, and this will 20 cause the gear mounted thereon to travel bodily on the internal gear so that a differential movement will be imparted to said movable gear. Means is provided for connecting this movable gear to the control cam, so that the gear will im- 25 part rotations to the control cam.

Referring more in detail to the drawings, the hand seamer comprises a rectangular frame consisting of a base member 1, standards 2, 2 connected to said base member, and a cap plate 3 30 which is secured to the upper ends of the standards 2, 2. The standards are preferably provided with reduced sections which are threaded and which extend through the cap plate, and a nut 4 attached to each standard, secures the 35 cap plate to said standards. Attached at the base of each standard 2 and to the base plate 1 is a clamping bracket 5. Each clamping bracket is provided with a clamping screw 6, and this 40 provides a means whereby the frame may be rigidly attached to a table or other support which is indicated at 7.

Mounted for rotation in the cap plate 3 is a shaft 8. Said shaft carries at the lower end 45 thereof a chuck 9. At the upper end of the shaft is a bevel gear 10 which meshes with a bevel gear 11 carried by the shaft 12 to which a crank 13 is attached. Said shaft 12 is journaled in the bearing extension of the cap plate 3. Said bearing extension is indicated at 14. A cover plate 15 is attached to the cap plate and bearing extension for covering the gears. Said cover plate is provided with an oil port 16 through which lubricating oil may be supplied to a port 17 in the 55

shaft and from this port in the shaft through radial ports to the bearings for the shaft.

The under face of the cap plate 3 is formed with a recess which is concentric to the axis of the shaft. Located on the inner face of the recess are gear teeth 18 which form an internal gear, the center of which is the axis of the shaft 8. The shaft 8 is provided with an eccentric section 19. Mounted on this eccentric section 19 is a gear 20 which meshes with the internal gear 18. Said gear 20 is caused by the rotation of the shaft to travel bodily on the internal gear, and for each revolution of the operating shaft, it will be given a portion of a rotation about its own axis. When the shaft 8 has been rotated a predetermined number of times, it will cause one rotation to the movable gear 20, and thus it is that the movable gear is given a differential movement from the shaft 8 which is rotated by hand.

The can to be seamed is indicated in broken lines at C in the drawings. Said can has a cover loosely applied thereto. The can is placed on a can support 21. This can support 21 is provided with a depending hub 22 which is mounted for free rotation in a supporting member 23. Said supporting member has a socket or recess to receive the hub 22. In the bottom portion of the recess is a spring plate 24. There is a central bore through the hub and threaded into said bore is a hardened cylinder 25. Said hardened cylinder has a spherical end which rests on the spring plate 24. Pivoted to the lower portion of the supporting member is a lever 26. Said lever 26 is mounted on a pivot rod 27 which is attached to the supporting member. This supporting member 23 is mounted for vertical movement in a sleeve 28 which is rigidly attached to the base plate 1 by bolts 29, 29. The sleeve 28 is provided with a slot 30 in one wall thereof, and the lever 26 extends through this slot. The lever 26 is provided with a cam face 31 which leads to a shoulder 32. When the parts are in the position shown in Fig. 1, then the can support 21 is lowered and a can may be placed thereon. When said lever is depressed to the position shown in Fig. 1a, then the cam face 31, riding on the supporting base 1, will lift the can support carrying the can and the end mounted thereon into engagement with the chuck. Thus it is that the can is chucked so that the rotating of the chuck will rotate the can and its support 21. When the lever 26 is in its depressed position, the shoulder 32 engages the base 1, and is so shaped as to positively hold the support in raised position. The spring plate 24 will yield to take care of any inequalities in the cans.

The first operation seaming roll is indicated at 33. Said roll is journaled on an arm 34 carried by a sleeve 35. This sleeve 35 is in turn mounted for free movement on the left-hand standard 2, as viewed in Fig. 4. A wear plate 36 is mounted on the standard 2 and rests on a shoulder 37 formed therein, and this sleeve 35 oscillates on this wear plate 36. A spring 38 is attached to this arm 34 and to a lug 39, and this spring operates to move the seaming roll 33 away from the chuck. Associated with the arm 34 is an operating lever 40. Said operating lever 40 is provided with a hub 41 intermediate its ends, and this hub is journaled on the standard 2 above the sleeve 35. Mounted on the lever 40 is a roller 42. This roller 42 cooperates with a face cam 43 formed on the cam supporting member or disk 44. The other end of the lever 40 is provided with

an adjustable abutment screw 45 which is adapted to engage the outer face of the arm 34. This limits the outward movement of the arm 34 through the action of the spring 38 thereon. The abutment screw 45 serves as a means for forcing the seaming roll into contact with the can parts, and it is adjustable for varying the tightness of the seam and also for positioning the seaming roll for operation on containers of different diameters. Also mounted in the end of the lever 40 is a compression spring 46 which bears against a shoulder 47 on the cap plate. This spring normally turns the lever 40 in a counter-clockwise direction as viewed in Figs. 2 and 3, thus causing the roller 42 to contact with the control cam 43 therefor.

The second operation seaming roll is indicated at 48. Said seaming roll is carried by an arm 49 journaled on the right-hand standard 2, as viewed in Fig. 4. A spring 50 operating on the arm 49 moves the roller 48 away from the chuck. Associated with this arm 49 is a lever 51 which is likewise journaled on the standard 2. Said lever 51 carries a roller 52 which cooperates with a cam face 53 formed on the cam supporting member 44. There is an adjustable abutment screw 54 carried at the outer end of the lever 51 and also a compression spring 55 which operates to move the lever 51 so as to hold the roller 52 in contact with this control cam.

The cam supporting member 44 is mounted for free rotation on the lower cap plate 56. This cap plate is attached to the cap plate 3 by suitable clamping bolts 57, 57 (see Fig. 4). The shaft 8 extends through this lower cap plate and is journaled therein. The chuck is secured to the shaft just beneath the lower cap plate 56. This lower cap plate has a hub 58 on its inner face, and the cam supporting member 44 is mounted for rotation on this hub 58. This cam supporting member is concentric to the shaft and rotates about the center of the shaft. Said cam supporting member is rotated in synchronism and timing with the traveling gear 20.

The cam supporting member 44 is provided with a series of recesses 59 which are similar in cross section. The centers of these recesses are concentric to the axis about which the cam supporting member rotates. The traveling gear 20 is provided with a similar series of pins 60. There is one pin for each recess. These pins are much smaller in diameter than the recesses, and the centers of the pins are concentric to the center of the traveling gear 20, and therefore, the centers of these pins are eccentric to the center of the cam supporting member 44. The diameter of the recess is substantially the same as the diameter of the pin, plus twice the eccentricity between the operating gear and the cam member, that is, the distance the center of the traveling gear is offset from the center of the actuating shaft.

After the can is chucked, then the shaft 8 is rotated through the hand crank 13. As this shaft is rotated, it will cause the gear to travel bodily on the internal gear and this will impart a certain angular movement or fraction of rotation to the gear 20 for each rotation of the shaft 8, or each rotation of the can. The connecting pins will positively impart the rotating movement given to the gear 20 through the turning of the crank to the control cam supporting member 44. These two parts rotate about different centers, but they rotate in timing and synchronism through this pin and recess connection join-

ing the parts. The pins will, of course, shift in the recesses as the movable gear changes its angular position about the center of the internal gear, but there will always be a positive connection imparting the movements of one to the other. This will give to the control cam a proper number of rotations for actuating the seaming levers and the seaming rolls controlled thereby. The control cam 43 for the first operation seaming roll 33 is provided with a depression 61. The control cam 53 operating on the seaming lever associated with the second operation seaming roll 48 is likewise provided with a depression 62. The depressions 61 and 62 are brought opposite the rollers 42 and 52, respectively, at the same time, and when in this position, the seaming rolls are moved to their extreme position away from the chuck. Said rolls are entirely free from the chuck, and at this time the can can be raised into engagement with the chuck ready for the seaming operation.

The cam supporting member 44 rotates in a counterclockwise direction, as viewed in Fig. 3, and as indicated by the arrow thereon. After 25 the can is chucked, then the shaft 8 is rotated. The cam 43 will move the roller 42 outward, thus bringing the seaming roll 33 in close to the flanges which are to be formed into a double seam. This cam face 43 from the point *a* to the point *b* is gradually increasing in radius so that the roller 42 is gradually moved outward, and the seaming roll forced inward to complete the first seaming operation. This inward movement of the first operation roll continues for a little less than 30 180 degrees movement of the cam 43. Meanwhile, the can has been given several revolutions, and the metal parts gradually rolled to complete the first seaming operation. This control cam 43 is then shaped, as shown in the drawings, so that 35 the seaming roll 33 will be moved out of contact with the seam and retained in an idle position until it again moves into the depression 61 so that it is entirely free of the chuck and the can seam ready for receiving another can. The control cam 53 from the point *c* to the point *d* is substantially concentric so that when this cam is 40 turning through a distance slightly less than 180 degrees, the second operation seaming roll 48 will be moved inward to a slight extent, but retained 45 in an idle position until after the first seaming operation has been performed. From the point *d* to the point *e*, the cam 53 is curved outwardly so that the second operation seaming roll is forced 50 into contact with the metal for completing the seaming operation and will be held with a very gradually increasing pressure as said control cam 53 continues its rotation, until finally the roller 52 moves into the depression 62 and this will release the second operation seaming roll from 55 contact with the chuck and the seam to permit the can to be removed from the chuck and replaced by another can for another seaming operation.

In Figures 7 to 9, there is shown a slightly modified form or construction embodying the broad basic principles which are described above. In this form of the invention, there is a supporting frame which includes standards 2a, 2a having a base member 1a formed integral therewith. Attached to the base plate are clamping brackets 5a, 5a for securing the frame to the table which is indicated at 1a. Mounted at the upper ends of the standards is a cap plate 3a, and journaled in this cap plate is a shaft 8a to which is attached a crank 13a. Mounted at the lower end

of the shaft 8a is a chuck 9a. Mounted on the supporting frame is a can support 21a. This can support is carried by a hub portion 22a which is mounted in a supporting member 23a and this supporting member is in turn mounted in a sleeve 28a attached to the supporting base member 1a by suitable clamping bolts. The cap plate 3a is provided with a recess having gear teeth 18a forming an integral gear similar to that above described. Located in this recess is a bodily traveling gear 20a. Said gear is journaled on an eccentric section 19a formed in the shaft 8a. The traveling gear 20a meshes with the internal gear 18a and travels around the same, so that a differential movement is given to this traveling gear 20a about its own axis by the rotation of the shaft 8a. Attached to the cap plate 3a is a lower cap plate 56a. This lower cap plate carries a journal bearing for the shaft 8a and has an upwardly extending sleeve bearing 58a 20 on which is mounted for rotation a cam supporting member 44a. This cam supporting member 44a is provided with a cam 43a with which the roller 52a cooperates. This roller is carried by a seaming lever which controls the seaming roll 48a. There is also a face cam 53a on this cam supporting member 44a which cooperates with a roller 42a carried by the seaming lever which controls the seaming roll 33a. These seaming levers and the connections for operating 25 the same are similar to those described above in detail, and further description thereof is not thought necessary.

The principal feature of difference between this modified form of construction and that shown in Figures 1 to 6, resides in the manner of operating the cam supporting member from the traveling gear 20a. The cam supporting member 44a is provided with a radial recess 63 having parallel walls. Mounted to slide freely in this radial recess is a block 64 which is carried by a pin 65 fixed to the traveling gear 20a. This pin 65 will travel concentrically about the axis of the traveling gear 20a. Its path of travel, however, is eccentric to the axis of rotation of the cam supporting member 44a. The block will slide radially in this groove to permit these parts to rotate about different centers, and at the same time, the rotating traveling gear will impart synchronizing rotations to the cam supporting member 44a.

It is obvious that changes can be made in the details of construction and the arrangement of the parts without departing from the spirit of the invention as set forth in the appended claims.

Having thus described the invention, what I claim as new and desire to secure by Letters Patent is—

1. A hand seamer for cans comprising a supporting frame, a shaft mounted therein for rotation, a chuck carried by said shaft, a stationary internal gear concentric to said shaft, a rotatable gear mounted within said internal gear and meshing therewith, means operated by said shaft for causing said gear to travel bodily on said internal gear, seaming rolls, seaming levers movable about fixed centers for operating said rolls, a member mounted for free rotation about the axis of the shaft, cams carried by said member for actuating said seaming levers, and means connecting said traveling gear to said cam supporting member whereby said member is caused to partake of the rotating movements of said gear.

2. A hand seamer for cans comprising a sup-

- porting frame, a shaft mounted therein for rotation, a chuck carried by said shaft, a stationary internal gear concentric to said shaft, a rotatable gear mounted within said internal gear and meshing therewith, means operated by said shaft for causing said gear to travel bodily on said internal gear, seaming rolls, seaming levers movable about fixed centers for operating said rolls, a member mounted for free rotation about the axis of the shaft, cams carried by said member for actuating said seaming levers, and means connecting said traveling gear to said cam supporting member whereby said member is caused to partake of the rotating movements of said gear, said last-named means including a driving pin fixed by one of said parts and extending into a recess formed in the other part.
3. A hand seamer for cans comprising a supporting frame, a shaft mounted therein for rotation, a chuck carried by said shaft, a stationary internal gear concentric to said shaft, a rotatable gear mounted within said internal gear and meshing therewith, an eccentric member carried by said shaft for rotatably supporting and causing said gear to travel bodily on said internal gear, seaming rolls, seaming levers movable about fixed centers for operating said rolls, a member mounted for free rotation about the axis of the shaft, cams carried by said member for actuating said seaming levers, and means connecting said traveling gear to said cam supporting member whereby said member is caused to partake of the rotating movements of said gear, said last-named means including a plurality of driving pins each extending into a recess formed in the other part.
4. A hand seamer for cans comprising a supporting frame, a shaft mounted therein for rotation, a chuck carried by said shaft, a stationary internal gear concentric to said shaft, a rotatable gear mounted within said internal gear and meshing therewith, means operated by said shaft for causing said gear to travel bodily on said internal gear, seaming rolls, seaming levers movable about fixed centers for operating said rolls, a member mounted for free rotation about the axis of the shaft, cams carried by said member for actuating said seaming levers, and means connecting said traveling gear to said cam supporting member whereby said member is caused to partake of the rotating movements of said gear, said last-named means including a plurality of driving pins each extending into a recess formed in the other part, said recesses being of such diameter as to permit the driving pins to contact with the walls of the recesses at all times during the rotation of the parts.
5. A hand seamer for cans comprising a supporting frame, a shaft mounted therein for rotation, a chuck carried by said shaft, a stationary internal gear concentric to said shaft, a rotatable gear mounted within said internal gear and meshing therewith, an eccentric member carried by said shaft for rotatably supporting and causing said gear to travel bodily on said internal gear, seaming rolls, seaming levers movable about fixed centers for operating said rolls, a member mounted for free rotation about the axis of the shaft, cams carried by said member for actuating said seaming levers, and means connecting said traveling gear to said cam supporting member whereby said member is caused to partake of the rotating movements of said gear, said last-named means including a plurality of pins fixed to said gear, each of which engages a

recess in the cam supporting member, said recesses being circular and of a diameter equal to the pin plus twice the eccentricity of the gear as to permit the pins to contact with the walls of the recesses continuously for imparting a positive rotation to said cam supporting member. 5

6. A hand seamer for cans comprising a supporting frame, a shaft mounted therein for rotation, a chuck carried by said shaft, a stationary internal gear concentric to said shaft, a rotatable gear mounted within said internal gear and meshing therewith, means operated by said shaft for causing said gear to travel bodily on said internal gear, seaming rolls, seaming levers movable about fixed centers for operating said rolls, 15 a member mounted for free rotation about the axis of the shaft, cams carried by said member for actuating said seaming levers, and means connecting said traveling gear to said cam supporting member whereby said member is caused to partake of the rotating movements of said gear, said cam supporting member having a radially extending groove formed therein, a block 20 slidably in said groove, and a pin carried by said gear and extending into said block for imparting 25 through said block rotations to said cam supporting member.

7. A hand seamer for cans comprising a supporting frame including standards spaced from each other, a base plate connecting said standards, a cap plate joining the upper ends of said standards, a shaft mounted in said cap plate for rotation about a vertical axis, a chuck carried by said shaft, a can support rotatably supported by the base plate, means whereby the can support may be raised to cause a can to engage the chuck, seaming rolls, seaming levers for actuating the seaming rolls, said levers being mounted for oscillation, respectively, about the standards, an actuating cam cooperating 40 with said seaming levers and mounted for independent rotation about the axis of said shaft, means for imparting to said cam a differential rotation from said vertical shaft, and hand means for rotating said vertical shaft. 45

8. A hand seamer for cans comprising a supporting frame including standards spaced from each other, a base plate connecting said standards, a cap plate joining the upper ends of said standards, a shaft mounted in said cap plate for 50 rotation about a vertical axis, a chuck carried by said shaft, a can support rotatably supported by the base plate, means whereby the can support may be raised to cause a can to engage the chuck, seaming rolls, seaming levers for actuating the seaming rolls, said levers being mounted for oscillation, respectively, about the standards, an actuating cam cooperating with said seaming levers and mounted for independent rotation about the axis of said shaft, means for 55 imparting to said cam a differential rotation from said vertical shaft, and hand means for rotating said vertical shaft, said means for raising the can support including a yieldable member on which said can support rests. 65

9. A hand seamer for cans comprising a supporting frame including standards spaced from each other, a base plate connecting said standards, a cap plate joining the upper ends of said standards, a shaft mounted in said cap plate for 70 rotation about a vertical axis, a chuck carried by said shaft, a can support rotatably supported by the base plate, means whereby the can support may be raised to cause a can to engage the chuck, seaming rolls, seaming levers for actuating 75

ing the seaming rolls, said levers being mounted for oscillation, respectively, about the standards, an actuating cam cooperating with said seaming levers and mounted for independent rotation about the axis of said shaft, means for imparting to said cam a differential rotation from said vertical shaft, hand means for rotating said vertical shaft, said means for raising the can support including a supporting member on which said can support is rotatably mounted, a lever pivoted to said supporting member, and means carried by the frame for guiding said supporting member, said lever having a cam face adapted to engage a frame for forcing the can support, upwardly when said lever is lowered.

10. A hand seamer for cans comprising a supporting frame including standards spaced from each other, a base plate connecting said standards, a cap plate joining the upper ends of said standards, a shaft mounted in said cap plate for rotation about a vertical axis, a chuck carried by said shaft, a can support rotatably supported by the base plate, means whereby the can support may be raised to cause a can to engage the chuck, seaming rolls, seaming levers for actuating the seaming rolls, said levers being mounted for oscillation, respectively, about the standards, an actuating cam cooperating with said seaming levers and mounted for independent rotation about the axis of said shaft, means for imparting to said cam a differential rotation from said vertical shaft, hand means for rotating said vertical shaft, said means for raising the can support including a supporting member on which said can support is rotatably mounted, a lever pivoted to said supporting member, and means carried by the frame for guiding said supporting member, said lever having a cam face adapted to engage a frame for forcing the can support, upwardly when said lever is lowered, said lever terminating in a shoulder adapted to engage the frame and retain said lever in a position for holding said can support raised.

11. A hand seamer for cans comprising a supporting frame, a shaft mounted therein for rotation about a vertical axis, hand means for rotating the shaft, a chuck carried by said shaft, a can support mounted for rotation on said supporting frame beneath said chuck, seaming rolls, independent actuating devices for said seaming rolls, a control cam for each of said devices, said control cams being mounted for rotation about the axis of said shaft, and means for imparting from said shaft to said control cams a differential movement relative to said shaft.

12. A hand seamer for cans comprising a supporting frame, a shaft mounted therein for rotation about a vertical axis, hand means for rotating the shaft, a chuck carried by said shaft, a can support mounted for rotation on said supporting frame beneath said chuck, seaming rolls, independent actuating devices for said seaming rolls, a control cam for each of said devices, said

control cams being mounted for rotation about the axis of said shaft, and means for imparting from said shaft to said control cams a differential movement relative to said shaft, means for raising said can support including a supporting member on which said support rotates, a yielding member mounted in said supporting member on which said can support rests, and a vertically moving lever connected to said supporting member for raising and lowering the same.

13. A hand seamer for cans comprising a supporting frame, a shaft mounted therein for rotation about a vertical axis, hand means for rotating the shaft, a chuck carried by said shaft, a can support mounted for rotation on said supporting frame beneath said chuck, seaming rolls, independent actuating devices for said seaming rolls, a control cam for each of said devices, said control cams being mounted for rotation about the axis of said shaft, and means for imparting from said shaft to said control cams a differential movement relative to said shaft, means for raising said can support including a supporting member on which said support rotates, a yielding member mounted in said supporting member on which said can support rests, an actuating sleeve carried by said frame in which said supporting member is mounted, a lever pivoted to said supporting member and having a cam face adapted to engage said frame for raising said supporting member for chucking the can, said cam face terminating in a shoulder adapted to retain said support in raised position.

14. A hand seamer for cans comprising a supporting frame, including spaced standards, a cap plate joining said standard, a shaft journaled in said cap plate for rotation about a vertical axis, a chuck carried by said shaft, seaming rolls, an arm supporting each seaming roll, said arms being mounted for oscillation, respectively, on said standards, an actuating lever for each arm mounted for oscillation, respectively, on said standards, a cam member actuated by said shaft for operating said seaming levers, a spring for each arm for moving the seaming roll outward away from the chuck, and an abutment carried by each lever for engaging its associated arm supporting the seaming roll.

15. A hand seamer for cans comprising a supporting frame, a shaft mounted therein for rotation about a vertical axis, a chuck carried by said shaft, a beveled gear attached to the upper end of said shaft, a horizontal shaft mounted in said frame having a bevel gear meshing with said first-named bevel gear, a crank for rotating said horizontal shaft, seaming rolls, an actuating lever for each seaming roll, a control cam for operating each lever mounted for independent rotation about the axis of said vertical shaft, and means actuated by said vertical shaft for imparting to said control cams a differential movement relative to said vertical shaft.

ALFRED L. KRONQUEST.
